Filed Oct. 9, 1973, Ser. No. 404,708

Term of patent 14 years

Int. Cl. D29—02

U.S. Cl. D10—111

FIG. 1

FIG. 2

FIG. 3

FIG. 4

FIG. 5

FIG. 6

FIG. 1 is a front isometric view of a bicycle reflector showing my new design;

FIG. 2 is a side isometric view of the reflector;

FIG. 3 is a side isometric view of the reflector with one of its snap members in clasping position;

FIG. 4 is a side isometric view of the opposite side of the reflector shown in FIG. 3;

FIG. 5 is a front isometric view of the reflector with both of its snap members in clasping position; and

FIG. 6 is a side isometric view of the reflector shown in FIG. 5.

The cross-hatching which indicates a conventional reflective surface is partially shown in FIGS. 1 through 6 for convenience of illustration, it being understood that the cross-hatching is uniformly continuous over the areas indicated.

I claim:

The ornamental design for a bicycle reflector, substantially as shown and described.
